HERMANN THUN, OF ESSEN, GERMANY, ASSIGNOR TO FRIED. KRUPP AKTIENGESELLSCHAFT, OF ESSEN-ON-THE-RUHR, GERMANY.

MEASUREMENT-STAMPING APPARATUS.

Application filed December 8, 1921. Serial No. 521,017.

To all whom it may concern:

Be it known that I, HERMANN THUN, residing at Essen, Germany, a citizen of the German Republic, have invented a certain 5 new and useful Improvement in Measurement-Stamping Apparatus, of which the following is a specification.

The present invention relates to stamping apparatus which are provided with more 10 than one type disc, and are used for the automatic stamping of the results of measurement, particularly for leather measuring machines. In a known apparatus of this kind it may happen that a value which differs considerably from the measured area 15 is printed on the leather to be measured up. The object of the present invention is to eliminate the possibility of this occurrence.

The invention will be described with reference to an example of the invention shown in the accompanying drawing in which:

Fig. 1 shows the means transferring the results of measurement to the stamping apparatus.

Fig. 2 is an axial section through the stamping apparatus.

Fig. 3 is a section on the line 3—3 of Fig. 2, seen from the left and

Fig. 4 is a diagrammatic view to facilitate comprehension.

To the graduation disc of the adding mechanism, which indicates in the well known way the measured area during the measuring operation, is connected by a chain 35 wheel A, a chain a^1 (see Fig. 1) and a chain wheel B through a spring R, a shaft b^1 , which rotates during the measuring operation in the direction indicated by the arrow w (see Fig. 3). The spring R enables the 40 shaft b^1 to be set to the zero position by a set screw r^1 mounted on the chain wheel B. In addition to this the spring R also serves for another purpose to be hereinafter described. On the shaft b^1 is rigidly fixed a 45 tappet or driver b^2 . This latter bears by means of a projection b^3 in the direction indicated by the arrow w (see Fig. 3) against a nut C. This nut C is mounted to move longitudinally, on the one hand, on a screw- 50 threaded sleeve b^4 made in one piece with the driver b^2 and on the other hand on a bolt d^1 which is mounted on a disc D which rotates on the shaft b^1 . The driver b^2 con-

sequently transmits rotation of the shaft b^1 in the direction of the arrow w to the disc 55 D. The nut C projects in an axial direction slightly less than one turn of its thread into the path of the projection b^3 on the driver b^2 (see Fig. 2).

To the disc D is rigidly attached a circular rack d^2 which contains 300 teeth and consists of 30 plates d^3 . Opposite the circular rack d^2 lies a locking pin e^2 , which is carried on one arm E of a double-armed lever E E^1 adapted to rock on a shaft F on the 60 frame of the machine. The other arm E^1 , of the lever E E^1 bears by means of a roller e^3 under the action of a weight e^4 against a cam g^1 . This latter is mounted on a hollow shaft G surrounding a shaft G^3 which has 65 to be rotated through 360° at each stamping operation, either by hand or mechanically. The inner side of the plates d^3 is stepped, ten steps being provided on each plate the 70 breadth of each step corresponding to the pitch unit of the circular rack d^2 . Opposite the stepped plates d^3 lies a stop pin h^2 , which is carried on one arm H of another double-armed lever H H^1 also adapted to 75 rock on the shaft F on the frame of the machine. This lever H H^1 bears by means of a roller h^3 under the action of a weight h^4 against another cam g^2 mounted on the hollow shaft G. The arm H of the lever H H^1 carries a toothed sector h^5 . This latter gears 80 into a pinion J, to which a type wheel J^1 is rigidly connected. This type wheel J^1 carries ten types numbered from 0 to 9 for hundredths of a square metre and lies in Fig. 2 on the left of the disc D. The arrangement is such that when the machine is 85 in the position of rest as shown in Fig. 3 the zero of the type wheel J^1 is not exactly opposite the place where the impression is to be made and the pin h^2 is slightly distant 90 from the step of the plate d^3 lying nearest to it.

On the disc D is provided a projection d^4 (see Fig. 2) which lies between the two ends of a U-shaped flat spring K (see Fig. 3). 100 This flat spring K embraces two tappet bolts d^6 fixed to a type wheel d^5 , so that an elastic coupling is provided between the disc D and the type wheel D^5 . This latter carries in accordance with the graduation on the indicating disc three series of types numbered 105

each from 0 to 9 and indicating tenths of a square metre. The entire periphery therefore corresponds to three square metres.

To the type wheel D^5 is rigidly connected a ratchet wheel D^7 , which has thirty teeth, so that to one pitch unit of the ratchet D^7 correspond ten pitch units of the circular rack d^2 . Opposite the teeth of the ratchet wheel D^7 lies a locking pin m^2 , which is carried on a double-armed lever $M M^1$ rotatable on a pin m^3 , the arrangement being such that, when the pin e^2 engages between two teeth of the circular rack d^2 , the pin m^2 is not opposite the point of any tooth, but on the contrary is displaced relatively to the tooth point next to it by an amount which, when the apparatus is in the zero position, is less than one tenth of the pitch unit but greater than 0, amounting preferably to one twentieth of the pitch unit while when the apparatus is in other positions it is equal to this amount increased by whole tenths of the pitch unit. When therefore the above mentioned amount is exactly one twentieth of the pitch unit, the pin m^2 can only assume the ten positions numbered 0 to 9 in Fig. 4 with respect to a gap between two of the teeth of the ratchet wheel D^7 .

The lever $M M^1$ bears by the aid of a roller m^4 under the action of a weight m^5 against another cam g^6 provided on the hollow shaft G and which is somewhat wider than the cam g^1 . To the type wheel D^5 and the ratchet wheel D^7 is rigidly connected a pinion d^8 which gears into a toothed wheel N . Between the toothed wheels N and d^8 there is a ratio of transmission of 3:10. If therefore the toothed wheel D^7 and with it the type wheel D^5 rotates three times, nine tenths of a revolution of the toothed wheel N correspond to this rotation.

The wheel N is elastically coupled by a U-shaped flat spring P to a third type wheel N^1 in a manner similar to that in which the disc D is coupled to the type wheel D^5 . The type wheel N^1 carries ten types numbered from 0 to 9 for whole square metres. To the type wheel N^1 is rigidly connected a ratchet wheel N^2 , to which a roller T is attached. A weight T^1 , which is attached by means of a band t^3 passing over a guide roller T^2 to the roller T , tends to permanently rotate this latter in a direction opposite to that indicated by the arrow y (see Fig. 3). The teeth of this ratchet wheel N^2 have a locking pin q^2 opposite to them, which is carried on a double-armed lever $Q Q^1$ rotatable around the pin m^2 .

In the zero position of the apparatus shown the zero of the disc N^1 is distant by a certain amount from the printing position. The arrangement is further such that when the pin m^2 enters a gap between two of the teeth of the ratchet wheel D^7 , the pin q^2 is not opposite the point of any tooth, on the

contrary is displaced relatively to the tooth point next to it by about one twentieth of the pitch unit of the ratchet wheel N^2 , increased, in the given case, by whole tenths of the pitch unit (see also Fig. 4). The free arm of the lever $Q Q^1$ bears by means of a roller q^3 under the action of a weight (not visible in the drawing) against a cam g^4 provided on the hollow shaft G . This latter is made somewhat wider than the cam g^6 .

When a piece of leather is being measured up, the chain wheel B , which rotates in agreement with the indicating disc of the adding mechanism, drives the shaft b^1 and this latter rotates in the direction of the arrow x (see Fig. 3). The rotation of the shaft b^1 is taken part in, through the medium of the driver b^2 and the nut C , which parts, when the shaft b^1 rotates in the direction of the arrow x , act as a rigid coupling between the shaft b^1 and the disc D , by the disc D and also, by means of the flat spring K , by the type wheel D^5 and consequently by the pinion d^8 . Its rotation is transmitted to the toothed wheel N and also by the aid of the flat spring P to the type wheel N^1 and this latter rotates against the action of the weight T^1 in the direction indicated by the arrow y (see Fig. 3) the band t^3 being thereby wound up on to the roller T .

When the measuring operation is over the type wheels D^5 and N^1 have thus been set to correspond to the area measured. During this time the type wheel D^5 has made more than one complete revolution, if the area measured exceeds three square metres. The shaft G^3 will now be rotated in the direction indicated by the arrow z (see Fig. 3). When this takes place the cam g^1 releases the lever $E E^1$ and the cam g^2 the lever $H H^1$ in close succession. In consequence thereof, the lever $E E^1$ rotates under the action of the weight e^4 in a counterclockwise direction, and the lever $H H^1$ rotates under the action of the weight h^4 in a clockwise direction (see Fig. 3). On the rotation of the lever $E E^1$ which takes place first, the locking pin e^2 drops into a gap between two of the teeth of the circular rack d^2 and rotates the disc D , until it strikes against the bottom of the gap between the teeth. The circular rack d^2 can therefore be rotated backwards or forwards with the disc D up to half a pitch unit or half one hundredth of a square metre (rounding off of the result of the measurement to hundredths of a square metre).

During the aforesaid rotation of the disc D the nut C is in one case lifted off the stop b^2 , while in the other case the shaft b^1 is rotated with it against the action of the spring R . Only now the exact setting of the type wheels does take place. The setting of the type wheel J^1 provided for the hundredths of a square metre depends upon the

position of the stepped plate d^3 which is now locked. As soon as the cam g^2 has released the lever $H H^1$, this latter swings under the action of the weight h^4 in a clockwise direction, until the stop pin h^2 strikes against that step, of the stepped plate d^3 which is opposite to it, and is adjusted by the dropping of the locking pin e^2 into the gap.

When the lever $H H^1$ is rocked the toothed sector h^5 rotates the toothed pinion J and the type wheel J^1 connected to it. The extent of the rotation depends on the adjustment of the particular stepped plate d^3 in question. Corresponding to the ten steps of the plate d^3 the type wheel J^1 can also only assume ten different positions, the arrangement being such that the types always come exactly into the printing position. On the further rotation of the shaft G^3 the cam g^6 (after the disc D and the type wheel J^1 have been adjusted) releases the lever $M M^1$, so that this latter rocks in a clockwise direction under the action of the weight m^5 .

The ratchet wheel D^7 has also been adjusted with the disc D . As already stated, the parts are so arranged that the point of a tooth can never be located opposite the locking pin m^2 after the disc D has been locked. If now therefore the locking pin m^2 strikes against the ratchet wheel D^7 , it always drops into a gap between two of the teeth, and into that one which corresponds to the rounded off result of measurement. The locking disc D^7 is rotated by the locking pin m^2 under the action of the weight m^6 against the action of the flat spring K until the locking pin m^2 has brought its point to the bottom of the respective gap. The type wheel D^5 has also been locked with the ratchet wheel D^7 and this in such a way that the correct type is located at the point where the impression is to be produced.

Finally after the further rotation of the shaft G^3 the lever $Q Q^1$ is also released, so that this latter rocks in a clockwise direction under the action of the respective weight. When this takes place the locking pin q^2 , as follows from what has already been said above, always drops into a gap between two teeth of the ratchet wheel N^2 and this into that particular one which corresponds to the rounded off result of measurement. It does so because by the dropping in of the locking pins e^2 and m^2 the parts N , N^1 and N^2 have been correctly adjusted for the dropping in of the locking pin q^2 . The ratchet wheel N^2 and, with it the type wheel N^1 , are rotated by the locking pin q^2 under the action of the aforesaid weight against the action of the flat spring P , until the locking pin q^2 has brought its point to the bottom of the respective gap. Now the type wheel N^1 is also locked in the correct position, so that when printing now takes place in the usual way a value is printed on the leather which can

at the most differ by plus or minus half a hundredth of a square metre from the exact value.

After the type wheels have been locked, the machine is reversed, in order to bring back the indicating disc to the zero position, so that the shaft b^1 rotates in a counter-clockwise direction. When this takes place, the stop b^3 is lifted off the nut C which is moved along the fixed bolt d^1 , in the direction indicated by the arrow v (see Fig. 2), owing to the rotation of the screw-threaded sleeve b^4 . Prior to the completion of one revolution of the shaft b^1 the nut C has moved out of the path of the stop b^3 , as it projected into this path less than one turn of the thread of the screw-threaded sleeve b^4 . In consequence hereof the shaft b^1 can continue to rotate without hindrance, until the indicating disc has been brought back to the zero position. In the meantime the stamping has taken place. After this the shaft G^3 continues to be rotated in the direction indicated by the arrow z , so that the cams mounted on the hollow shaft G rock the levers $Q Q^1$, $M M^1$, $H H^1$ and $E E^1$ back into their original positions again. When this takes place the various locking pins are disconnected from the corresponding toothed or ratchet wheels and these latter return together with the type wheels to their zero positions under the action of the weight T^1 .

When the type wheel D^5 is rotated backwards the nut C carried by the disc D is shifted in a direction opposite to that indicated by the arrow v on the screw-threaded sleeve b^4 which is now locked, until the nut C , finally, and at the instant in which the apparatus has returned to its zero position, comes into contact with the driver b^2 , which prevents any further rotation of the shaft D . The return of the type wheel J^1 to its zero position takes place immediately when the lever $H H^1$ is rotated by means of the toothed sector h^5 .

Claims:

1. In a stamping apparatus of the character described, a plurality of type discs, locking means for each of said type discs, and controlling means for said locking means, said controlling means so coacting with said locking means that the locking means for the type disc for the lowest unit is first, and after it that for the type disc for the next higher unit, is operated.

2. In a stamping apparatus of the character described, a plurality of type discs, locking means for each of said type discs, said locking means comprising a ratchet wheel and a locking member cooperating therewith, controlling means for said locking means, said controlling means so coacting with said locking means that the locking means for the type disc for the lowest unit is first, and after it that for the type disc for

the next higher unit, is operated, and elastic coupling means connecting the ratchet wheel of the type disc for the lower unit with the ratchet wheel of the type disc of the next higher unit.

3. In a stamping apparatus of the character described, a plurality of type discs, locking means for each of said type discs, said locking means comprising a ratchet wheel and a locking member cooperating therewith, the ratchet wheels and locking members of the type discs for two successive units being so arranged relatively to each other that when the corresponding locking member engages with the ratchet wheel of the type disc for the lower unit, the locking member of the ratchet wheel of the type disc for the next higher unit is always opposite that gap between two of the teeth of this ratchet wheel which corresponds to the figure to be printed, controlling means for said locking means, said controlling means so coacting with said locking means that the locking means for the type disc for the lowest unit is first, and after it that for the type disc for the next higher unit, is operated, and elastic coupling means connecting the ratchet wheel of the type disc for the lower unit with the ratchet wheel of the type disc of the next higher unit.

4. In a stamping apparatus of the character described, a plurality of type discs, locking means for each of said type discs, said locking means comprising a ratchet wheel and a locking member cooperating therewith, said locking means being so arranged that when the ratchet wheel of the type disc for the lower unit is in the zero position, the locking member of the ratchet wheel of the type disc for the next higher unit is displaced relatively to the next tooth of this ratchet wheel by an amount which is equal to the pitch unit of the same divided by the double of the number of positions this locking member can assume with respect to any single gap between the teeth, controlling means for said locking means, said controlling means so coacting with said locking means that the locking means for the type disc for the lowest unit is first, and after it that for the type disc for the next higher unit, is operated, and elastic coupling means connecting the ratchet wheel of the

type disc for the lower unit with the ratchet wheel of the type disc of the next higher unit.

5. In a stamping apparatus of the character described, a plurality of type discs, locking means for each of said type discs, said locking means comprising a ratchet wheel and a locking member cooperating therewith, stepped stops carried by the ratchet wheel of the type disc for the lowest unit, a rocking toothed sector positively connected to the type disc for the lowest unit, a stop pin mounted on said sector and adapted to coact with said stepped stops so that according to the position of said stepped stops, the stop pin together with the toothed sector and the type disc for the lowest unit can travel over a greater or lesser distance, and controlling means for said locking means, said controlling means so coacting with said locking means that the locking means for the type disc for the lowest unit is first, and after it that for the type disc for the next higher unit, is operated.

6. In a stamping apparatus of the character described, a plurality of type discs, locking means for each of said type discs, said locking means comprising a ratchet wheel and a locking member cooperating therewith, a driving shaft for said stamping apparatus, the ratchet wheel of the type disc for the lowest unit being loosely mounted on said driving shaft, a stop mounted on said driving shaft, a screw threaded portion on said driving shaft, a bolt mounted on the ratchet wheel of the type disc for the lowest unit, a nut mounted on the screw threaded portion of the driving shaft, and adapted to be axially movable on said bolt, the stop on said driving shaft engaging said nut in driving relation, said nut projecting less than one turn of its thread in an axial direction into the path of said stop and controlling means for said locking means, said controlling means so coacting with said locking means that the locking means for the type disc for the lowest unit is first, and after it that for the type disc for the next higher unit, is operated.

The foregoing specification signed at Essen, Germany, this 8th day of November, 1921.

HERMANN THUN.
